UNITED STATES PATENT OFFICE

WILLIAM H. GEBHARDS, OF PHELPS CITY, MISSOURI

MILK-BOTTLE HOLDER

Application filed May 24, 1928. Serial No. 280,255.

This invention relates to a milk bottle holder and it is an object of the invention to provide a device of this kind which may be readily applied to a post or other support and which, when not in use, automatically assumes a compact adjustment.

Another object of the invention is to provide a device of this kind with which a bottle may be readily engaged and whereby the 10 bottle is held in a position out of the way of small children, cats and dogs and also in a manner whereby the bottle may be readily and conveniently removed.

The invention consists in the details of 15 construction and in the combination and arrangement of the several parts of my improved milk bottle holder whereby certain important advantages are attained and the device rendered simpler, less expensive and 20 otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawing, wherein:—

Figure 1 is a view in side elevation illustrating a milk bottle holder constructed in 30 accordance with an embodiment of my invention and in working position, a portion being in section;

Figure 2 is a view partly in section and 35 partly in top plan of the cup-like member and associated parts as herein embodied;

Figure 3 is a fragmentary vertical sectional view taken through the structure illustrated in Figure 2;

Figure 4 is an elevational view of the supporting plate for the cup-like member as herein set forth;

Figure 5 is a view in top plan of the clip for the top portion of the bottle unapplied.

As disclosed in the accompanying drawing, 45 1 denotes a cup-like member of requisite dimensions and which in use is adapted to receive the base portion of a bottle. The side flange 2 of the member 1 is provided at its upper portion with a radially disposed arm

3, said arm being relatively broad and provided adjacent to its outer end with a groove or channel 4 extending transversely thereacross and which is adapted to receive a portion of a pivot bolt 5. The arm 3 is maintained in requisite engagement with the pivot bolt 5 by a bearing plate 6 bolted or otherwise secured to the arm 3 and provided with a groove or channel 7 adapted to register with the groove or channel 4 hereinbefore referred to.

The pivot bolt 5 is also disposed through the spaced aligned knuckles 8 provided on the plate 9 and between which the arm 3 is snugly received. The plate 9 is adapted to be mounted in any desired manner, as by screws or the like upon a face of a post or other support.

The plate 9 is provided with a ledge 11 with which the outer end portion of the arm 3 contacts to limit the downward swinging movement of the member 1.

Operatively engaged with the pivot bolt 5 at opposite sides of the arm 3 are the coiled springs 12 provided at the end portions of an outstanding elongated frame 14 which underlies the member 1 and has its outer end portion inserted through the slits 15 produced in the bottom wall of the member 1 whereby said frame is effectively engaged with said member.

The outer end portion of each of the springs 12 is provided with an extension 17 operatively engaged with the plate 9 to assure the requisite functioning of the spring. It is to be understood that as the member 1 is swung downwardly each of the springs 12 is placed under tension so that when the member 1 is relieved of load the springs will serve to automatically throw the member 1 upwardly into close contact with the associated post or other support with which the device may be applied.

With the base portion of a bottle received within the member 1, an elongated loop member or clip 18 is engaged around the neck portion of the bottle, said loop member or clip 18 being hingedly connected for swinging movement in a vertical direction to the post or support, as indicated at 19. The outer

extremities of the loop member or clip 18 are provided with the rubber knobs or tips 20 and if desired the side wall 2 of the member 1 may have disposed over the inner face 5 thereof the clips 21 to assure an effective fitting of the base portion of the bottle within the member 1.

In practice it is to be understood that the member 1 will be positioned upon a post or other supporting surface a distance sufficient 10 above the floor level to prevent ready access thereto by small children or by cats and dogs, and it will also be readily seen that the construction of the holder herein- 15 before described is such to permit the bottle to be readily applied or removed. Furthermore, it is to be noted that when the bottle is removed the member 1 will at once swing upwardly against the adjacent face of the 20 post or other support and that the clip or loop member 18 will readily drop down to such position so that when the device is not in use these members are out of the way.

From the foregoing description it is 25 thought to be obvious that a milk bottle holder constructed in accordance with my invention is particularly well adapted for use by reason of the convenience and facility with which it may be assembled and operated, 30 and it will also be obvious that my invention is susceptible of some change and modification without departing from the principles and spirit thereof and for this reason I do not wish to be understood as limiting myself 35 to the precise arrangement and formation of the several parts herein shown in carrying out my invention in practice except as herein-after claimed.

I claim:—

- 40 1. A bottle holder comprising, in combination, a member having a side flange to provide a cup-like formation to receive the base portion of a bottle, an outstanding arm carried by the upper portion of the flange, a pivot bolt, means for engaging the outer end portion of the arm to the pivot bolt, members with which the pivot bolt is engaged, the arm being positioned between said members, a frame contacting with the bottom of the cup- 45 like member and having spaced extremities, coil springs carried by said extremities of the frame and encircling the pivot bolt at opposite sides of the arm, said springs being operatively engaged with the supporting mem- 50 bers for the bolt, said springs exercising a tension for automatically raising the cup-like member when free of load, and means for limiting the downward swinging movement of the arm.
- 60 2. A bottle holder comprising, in combination, a member having a side flange to provide a cup-like formation to receive the base portion of a bottle, an outstanding arm carried by the upper portion of the flange, a pivot bolt, means for engaging the outer end

portion of the arm to the pivot bolt, members with which the pivot bolt is engaged, the arm being positioned between said members, a frame contacting with the bottom of the cup-like member and having spaced extremities, coil springs carried by said extremities of the frame and encircling the pivot bolt at opposite sides of the arm, said springs being operatively engaged with the supporting members for the bolt, said springs exercising a tension for automatically raising the cup-like member when free of load, and means for limiting the downward swinging movement of the arm, the bottom of the cup-like member being provided with spaced slits through which the outer portion of the frame is inserted to positively connect said frame to the cup-like member.

In testimony whereof I hereunto affix my signature.

WILLIAM H. GEBHARDS.
